UNITED STATES PATENT OFFICE.

FRANK M. BROOKS, OF NEW YORK, N. Y.

GAS-BURNER.

1,104,473.

Specification of Letters Patent. Patented July 21, 1914.

Application filed April 1, 1914. Serial No. 828,746.

To all whom it may concern:

Be it known that I, FRANK M. BROOKS, a citizen of the United States, residing in the borough of Brooklyn, county of Kings, city 5 and State of New York, have invented an Improvement in Gas-Burners, of which the following is a specification.

As is generally known, the so-called semi-indirect artificial lighting effects are in 10 much demand at the present time. These lighting effects are obtained by suspending a transparent or translucent bowl and placing a suitable light within the same. In the use of electric lights, there is little or no 15 difficulty in producing this effect, as the necessary lead wires may be readily brought to a lamp socket or sockets fixed within the bowl, or within the frame supporting the same.

20 My present invention relates to a gas burner, and particularly to an inverted gas burner. I am aware that heretofore inverted gas burners have been applied to the end of a supply pipe in such a manner that 25 they might be inserted within a suitable bowl to produce this semi-indirect lighting effect, but the object of my present invention is the provision of an inverted gas burner for such use and so constructed that in the fixture 30 made in accordance with my invention the gas cock proper is removed or offset from the burner so as to be out of the immediate heat zone directly above the same, and furthermore the construction of the fixture is 35 such that the burner and cock are contained within the bowl and the key of the gas cock provided with a stem of sufficient length to extend to a point beyond the rim of the bowl, so that it may be operated exteriorly 40 thereof.

In carrying out my invention, I prefer to employ a gas cock fitted with a key, as is 45 customary, and having offset portions, a suitable connection from one of these offset portions to the gas supply pipe, and by 50 which the gas cock and burners are supported, elbows or L-shaped nozzles connected to the other offset portion, and burner tubes for inverted burners attached 55 to the elbows, all of which, together with the details of construction, will be herein-after more particularly described.

In the drawing, Figure 1 is a side elevation and partial cross section illustrating my 55 improved gas burner. Fig. 2 is a cross section on line $\alpha\alpha$, Fig. 1, and Figs. 3 and 4 are

views similar to Fig. 1, illustrating modified forms of the invention.

Referring to the drawing, and particularly to Figs. 1 and 2, my improved gas 60 burner preferably comprises a gas cock 10, fitted, as is customary, with a key 11, to which is suitably attached a stem 12. The key 11 is secured in position in the gas cock by means of a screw 15 and washer 16, as is 65 customary, and is provided with a pin 13 adapted to abut against the shoulders 14, formed in the body of the gas cock, to act as stops for limiting the revoluble movement of the key. The body of the gas cock 70 10 is provided with offset portions, indicated at 17 and 18 respectively. These are shown at right angles to each other, but as will be understood, may be placed in any required relationship to the body of the gas cock. 75 The offset 17 is provided with a tapped opening in which one end of a nipple 19 is connected, the opposite end of which is secured in a similarly tapped opening in a socket 20. The socket 20 is connected to the 80 lower end of a supply pipe 21, which, as is customary, passes through a canopy 22, and from which, by chains 23 or otherwise, a frame 24 and bowl 25 may be suspended, the bowl 25 being maintained in position within 85 the frame 24 by means of thumb screws 26, or otherwise. In this manner, as will be apparent, the gas cock 10 is supported in an offset position from the supply pipe 21. Suitably secured in and extending in opposite 90 directions from the offset portion 18 of the gas cock are corresponding arms of elbows or L-shaped nozzles 27 and 28. Each of the other arms of these elbows is fitted with a burner tube 29, including needle gas 95 regulating valves 30 and air regulating valves 31, and mantle supports or mouth pieces 32 adapted to receive inverted mantles 33, the burner tubes 29 being so shaped that the mantles 33 are placed approximately 100 centrally of the bowl when in position.

The stem 12, attached to the key 11, is sufficiently long to extend beyond the rim of the frame and bowl, and at its extremity may be provided with a cross arm 34, at the 105 ends of which are attached suitable pull chains 35 and 36, for operating the key to turn on or shut off the supply of gas. Furthermore, as is readily apparent, by reference to Fig. 1, the burner may be provided 110 with a pilot light 37 connected by means of a tube 38 with the socket 20, and the supply

of gas to the pilot light may be controlled by a screw control valve 39, the pilot light 37, as will be understood, being preferably placed between the mantles 33.

5 From the foregoing description, it will be apparent that the lights, that is to say, the mantles, are placed approximately in the central portion of the globe, and that the gas cock 10, controlling the admission of gas 10 to the burner tubes and mantles, is offset to such an extent as to be removed from the heat zone directly above the lights, the extent to which the gas cock may be removed being limited by the diameter of the bowl, 15 and determined by the length of the nipple 19. It will be further apparent that the gas cock and connections lie entirely within the diameter of the bowl while the end of the stem 12, with its cross arm 34 and pull 20 chains 35 and 36, lie exteriorly of the bowl, so as to provide for a ready operation of the gas cock.

Referring to Fig. 3, it will be seen that I may dispense with the central depending 25 supply pipe 21, which, in this instance, may terminate immediately below the canopy 22, where a socket 42 is connected to the same, the nipple 43 being connected at one end to the socket 42 and at its opposite end to a 30 socket 41, the connecting and suspending pipe 40 being secured at one end in the socket 41 and at the opposite end in the offset portion 17 of the gas cock. In this construction, as will be apparent, the pipe 40 35 may be set at the same or approximately the same inclination as the chains 23, by which the frame and bowl are supported, so as to make the fittings as inconspicuous as possible, the socket 41 and the offset portion 17 of 40 the gas cock being tapped, at suitable angles, to make this construction possible. Furthermore, by reference to Fig. 4, it will be seen that the ring and bowl may be supported by a series of pipes or tubes 44, any one 45 of which may also be employed as a gas supply tube for conveying the gas from the supply pipe to the gas cock, the other features of this burner being precisely similar to those hereinbefore described in the other 50 and preferred forms of the invention.

I claim as my invention:

1. An inverted gas burner comprising a gas cock fitted with a key and stem, offset portions at the sides of the gas cock, a nipple 55 secured at one end in one of the said offset portions, and adapted at its opposite end to be connected to a gas supply pipe, nozzles

connected to and leading from the other offset portion of the gas cock, burner tubes attached to the said nozzles, and means at 60 the ends of the said burner tubes for supporting the gas mantles.

2. An inverted gas burner, comprising a gas cock fitted with a key, offset portions at the sides of the said gas cock, a socket, a 65 nipple secured at one end to the said socket, and at the other end in one of the said offset portions, elbow nozzles leading from the other offset portion, burner tubes attached to the elbow nozzles, mouth pieces at the extremities of the said burner tubes, adapted to receive inverted gas mantles, and means in the said burner tubes for regulating the admission of air and gas thereto.

3. In a gas fixture, in combination with a 75 bowl and means for supporting the same, a gas cock fitted with a key and key stem, offset portions at the sides of the gas cock, a nipple secured at one end in one of the said offset portions and adapted at its opposite 80 end to be connected to a gas supply pipe, nozzles leading from the other offset portion, and burner tubes attached to the said nozzles, the gas cock, offset portions and burner tubes being located within the said 85 bowl and the stem secured to the said key extending beyond the rim of the said bowl so that the key may be operated exteriorly thereof.

4. In a gas fixture, in combination with a 90 bowl and means for supporting the same, a gas cock fitted with a key, offset portions connected to the body of the said gas cock, a socket, a nipple secured at one end in the 95 said socket and at the other end in one of the offset portions of the said gas cock for supporting the same and the parts attached thereto, elbow nozzles leading from the other offset portion, burner tubes attached to the said elbow nozzles, mantle supports 100 fitted at the extremities of the said burner tubes, the said gas cock, elbow nozzles and burner tubes being located within the said bowl, and a stem secured to and extending from the said key beyond the rim of the said 105 bowl so that the key may be operated exteriorly thereof.

Signed by me this 27th day of March, 1914.

FRANK M. BROOKS.
